UNITED STATES PATENT OFFICE.

LOUIS KRONTHAL, OF NEW YORK, N. Y.

ADJUSTABLE SWEAT-BAND FOR HEADWEAR.

1,194,193.

Specification of Letters Patent. Patented Aug. 8, 1916.

Application filed September 22, 1915. Serial No. 51,894.

To all whom it may concern:

Be it known that I, LOUIS KRONTHAL, a citizen of the United States, and a resident of the city of New York, borough of Manhattan, in the county and State of New York, have invented a new and Improved Adjustable Sweat-Band for Headwear, of which the following is a full, clear, and exact description.

10 My invention relates to self-adjustable sweat bands for headwear, and an object thereof is to provide a simple, convenient and inexpensive sweat band which coöperates with a self-adjusting band of headwear, 15 and which sweat band will automatically take up any increase in size of the band of the headwear.

With the above and other objects in view, the nature of which will more fully appear 20 as the description proceeds, the invention consists in the novel construction, combination and arrangement of parts as herein fully described, illustrated and claimed in the accompanying drawings forming part of 25 the application.

Similar characters of reference indicate corresponding parts in all the views.

Figure 1 is a perspective view of a headwear, partly in section at different places to 30 illustrate the details of construction; Fig. 2 is a perspective view of a section of the sweatband and a section of the expandible band of the headwear secured thereto; and Fig. 3 is a horizontal section through the 35 sweat band and expandible band of the headwear in Fig. 1.

Referring to the drawings, 4 represents the expandible band of the headwear. 5. The expandible band is formed of two substantially inelastic sections 6 and 7, the ends 40 of each section being connected by an elastic portion 8. The section 7, and its elastic part 8 are connected to the body of the headwear 5. The section 6 with its elastic portion 8 encompasses the section 7 with its elastic portion, and it is only connected at one point 45 with its inelastic part with the elastic part 8 of the section 7. This prevents the section 6 from moving on the section 7 without preventing the expansion of either of the 50 elastic portions 8. By securing the central part of the section 6 to the central part of the elastic portion 8 of the section 7, the two sections 6 and 7 are disposed symmetrically.

Secured to the lower edge of the inelastic section 6 is a sweat band section 9 of moisture-proof material, and a somewhat similar sweat band section 10 is secured to the lower edge of the inelastic portion 7. The sweat band section 9 has slits 11 adjacent the ends thereof through which the ends of the sweat band section 10 project, as best shown in Figs. 1 and 3. A portion of the sweat band section 10 adjacent each end thereof is left unsecured, as shown at 12, to the inelastic section 7 so as to allow freedom of movement to the sweat band section 9 when the size of the band 4 is varied.

It is self-evident that in place of providing slits at each end of the sweat band section, a slit 11 may be provided only at one end thereof while the other end of the sweat band section 10 may be directly secured to the sweat band section 9. By providing an extensible sweat band with an expandible band for a headwear, a more comfortable headwear results as an ordinary expandible band of a headwear is not comfortable without a sweat band.

I claim:

1. In a headwear, an expandible band and an endless sweat band formed of sections of moisture-proof material, said sections being associated with the expandible band, said sweat band sections including means for compensating for the increase or decrease in size of the expandible band.

2. In a headwear, an endless expandible band and an extensible sweat band of moisture-proof material associated with the expandible band, substantially as and for the purposes set forth.

3. In a headwear, an expandible band formed of inelastic and elastic sections, and sweat band of sweat-proof material sections each secured to the inelastic section of the expandible band, said sections of the sweat band having interengaging means whereby they can move relatively to one another when the size of the expandible band is varied.

4. In a headwear, an expandible band comprising an inelastic portion, the ends of which are secured by an elastic portion, said inelastic and elastic portions being secured to the body of the headwear, a second inelastic portion, the ends of which are secured by an elastic portion encompassing said first mentioned inelastic and elastic portions, said

2
second inelastic portion being disposed symmetrically to the first inelastic portion, means securing the second inelastic portion to the central part of the first mentioned elastic portion; and a sweat band section secured to each inelastic portion at the lower edges thereof, one of said sweat band sec-

tions having slits at the ends thereof through which the ends of the other sweat band section projects.
